UNITED STATES PATENT OFFICE.

WILLIAM B. GUERNSEY, OF NORWICH, AND WILLIAM B. TURNER, OF NEW YORK, N. Y., ASSIGNEES OF ONE-THIRD TO THE TORREY AUTOMATIC BRAKE COMPANY, OF NEW YORK.

LOCOMOTIVE OR CAR BRAKE.

SPECIFICATION forming part of Letters Patent No. 278,429, dated May 29, 1883.

Application filed June 2, 1882. (No model.)

To all whom it may concern:

Be it known that we, WILLIAM B. GUERNSEY, of Norwich, in the county of Chenango, and WILLIAM B. TURNER, of New York, both 5 in the State of New York, have invented certain new and useful Improvements in Brakes for Locomotives or Railway-Cars, of which the following is a specification.

Our invention relates to a power-brake; and 10 it consists, first, in mounting brake-shoes directly upon their operating-cranks; second, in a driver-brake for locomotives, in which the brake-shoes are mounted directly on their operating-cranks, as hereinafter described; third, 15 in the combination of brake-shoes mounted upon their operating-cranks, supplementary arms, and connecting-rod, all arranged nearly in the plane of the driving-wheels, as herein-after described; fourth, in the combination of 20 brake-shoes pivoted on operating-cranks with a system of lever-arms, connecting-rod, an equalizing-lever, and a suitable motor, substantially as herein described.

In the accompanying drawings, Figure 1 is a 25 side elevation, representing the driving-wheels of a locomotive with our invention applied. Fig. 2 is a front view of one of the double cranks employed for carrying and moving the brake-shoes, as herein described.

30 A A' are boxes attached to the frame of the locomotive behind and in front of the driving-wheels W, respectively. Within these boxes are journaled the brake-shafts B B', carrying at their outer ends the arms C C', upon the 35 outer ends of which the brake-shoes S S' are pivoted. On the inner ends of the shafts B B' are the brake-operating arms D D'; or said arms may be attached to the shafts outside of the locomotive-frame.

40 A primary draw-rod is shown at E, connected with a suitable motor and with each alternate crank-arm D, so as to apply pressure to the shoes S on one side of each wheel. The draw-rod E extends to an equalizing-lever, F, fulcrumed at f in a suitable box, H, and having hinged to its opposite end a second draw-rod, G, connected to the other alternate arms, D', so that by the pull of the primary draw-rod E an equal and simultaneous 45 movement will be communicated to all the shoes S S' on the opposite sides of the respect-

ive wheels. Equalizers of any appropriate form may be placed elsewhere—as, for instance, on the levers D D', or some of them—to effect the same purpose. When the pressure is relieved, 55 the shoes are retracted by springs or in any preferred or convenient manner.

It will be observed that in our improved 60 brake the shoes are not merely operated by cranks, but are carried upon their operating cranks, being swiveled directly to them, while another crank-arm on the opposite end or upon the same end of the shaft which carries the shoe-crank is used to operate the said cranks for the purpose of applying the pressure to the shoes.

Our improved brake dispenses entirely with 65 the need of hangers, levers, pitmen, and guides, and has neither outside nor overhead connections.

All the shoes on one side are operated by 70 longitudinal rods or chains inside of or below the locomotive-frame, each rod being attached to the actuating crank-arms of its respective 75 shoes, which have their concavities and their proper motion in like direction, while an equalizer at one end of the system converts a pull at the other end upon one of the rods into a pull upon them both. All the shoes move through 80 equal distances, irrespective of pressure.

In describing the use of separate short crank-shafts on each side we refer, of course, to the application of the invention to locomotive-brakes. It is manifest that it is alike applicable to car-brakes either by using short shafts, 85 as above described, or by using through-shafts with a single motor-arm for each shaft, which carries at its respective ends the shoe-arms for the two wheels of one axle.

Having thus described our invention, what 90 we claim as new, and desire to secure by Letters Patent, is—

1. In a locomotive-brake, the combination, 95 with a series of carrying-wheels rigidly connected, so as to partake of each other's movements of rotation, of a series of rock-shafts, each carrying a brake-shoe and fulcrumed upon the vehicle-frame, and a series of actuating-rods connecting alternately with the rock-levers, the system thus arranged operating to 100 move the brake-shoes in unison and through exactly equal distances, the levers and shoes

and connections constituting a complete set upon one side of the vehicle, wholly independent of the set upon the opposite side of such vehicle.

- 5 2. In a locomotive-brake, crank-shafts swiv-
eled to the vehicle-frame or to attachments
thereto, carrying brake-shoes upon one end
and attached alternately to longitudinal op-
erative rods or equivalents, the two systems
10 of rods being themselves connected at one end
by an equalizer, the whole in such wise as will
cause any movement communicated through
the rods to move each of the said brake-shoes
through exactly equal distances, substantially
15 as set forth.
3. In a locomotive or car brake, the boxes

A, A', and H, attached to the vehicle-frame,
in combination with the shafts B B', journaled
in said boxes A A' and carrying arms C C',
to the outer ends of which the shoes S S' are 20
pivoted, and the arms D D', the equalizer F,
journaled pivotally in the box H, the draw-
rod E, connected to one end of the equalizer
F and to the arms D, and the draw-rod G,
connected to the opposite end of the said equal- 25
izer F and to the arms D', substantially as and
for the purposes specified.

WILLIAM B. GUERNSEY.
WILLIAM B. TURNER.
